CLAIM

We claim the ornamental design for an extractor port housing, as shown and described.

DESCRIPTION

FIG. 1 is a bottom isometric view of an extractor port housing showing our new design.

FIG. 2 is a front view thereof;

FIG. 3 is a rear view thereof;

FIG. 4 is a left side view thereof;

FIG. 5 is a top view thereof; and,

FIG. 6 is a bottom view thereof.

The broken lines form no part of the claimed design.

1 Claim, 3 Drawing Sheets# US D701,661 S
